LADDER COUNTERBALANCING APPARATUS

Herman J. Troche, Cleveland Heights, and Alvin J. Farrar, Cleveland, Ohio, assignors to The American Coach & Body Company, Cleveland, Ohio, a corporation of Ohio

Application May 3, 1945, Serial No. 591,756

8 Claims. (Cl. 228—13)

1

This invention relates to a utility vehicle having a ladder thereon that is swingable and tiltable with reference to the vehicle for obtaining access to overhead traffic lights, streetlamps and the like. The invention comprises in general an improvement on the ladder construction that is shown in United States Letters Patent No. 2,238,665, issued April 15, 1941, for Utility vehicle on an application filed by Herman J. Troche.

Briefly, the ladder illustrated in the aforesaid patent is supported upon a sleeve which in turn is supported upon a column that is attached to the vehicle floor. The ladder is counterbalanced by spring loaded plungers which are disposed at each side of the support within casings and which are connected to the ladder by flexible cables. While such spring suspension is adequate to counterbalance the ladder, nevertheless we have found that in certain elevated positions of the ladder the force exerted by the counterbalancing mechanism is not applied with sufficient degree of uniformity in the entire range of tilting movement of the ladder, as a result of which more force must be exerted by the operator to shift the ladder whenever it is in one position than when it is disposed in another position.

An object of the present invention is to improve the counterbalancing mechanism so as to achieve a counterbalancing force that will be substantially uniform in its counterbalancing effect for substantially the entire range of tilting movement of the ladder whereby the aforesaid difficulty may be readily overcome.

A more specific object of the present invention is to provide a counterbalancing mechanism which, as the ladder is tilted toward a vertical position, will decrease its force substantially commensurate with the decrease of the force of gravity which tends to return the ladder to a horizontal position.

Other objects and advantages of the invention will become more apparent from the following description, reference being had to the accompanying drawings, which illustrate a preferred embodiment of the invention. The novel features of the invention will be summarized in the claims.

Referring now to the drawings, Fig. 1 is a fragmentary view of a vehicle having a ladder embodying the present invention, mounted thereon and illustrating the ladder in various positions; Fig. 2 is a fragmentary side elevation of a ladder and supporting structure and illustrates the ladder in a horizontal position for transportation from place to place, certain parts being broken away to more clearly illustrate the invention;

2

Figs. 3 and 4 are views similar to Fig. 2 illustrating different tilted positions of the ladder; Fig. 5 is a fragmentary plan view of the ladder and supporting structure, the ladder being in the position shown in Fig. 3.

In the drawings, the ladder is shown as being mounted upon the floor of a vehicle, indicated in general at 10, and is of the extensible type, there being two sections 11 and 12. The sections are mounted telescopically with respect to each other in the customary manner, the section 11 being the lower or base section and the section 12 being the upper or extensible section.

The ladder is supported on the vehicle for swinging movement in an entire circle with reference thereto, and for tilting movement to any desired angle within its range. The supporting structure for the ladder may comprise a column in the form of a cylinder 14 that projects upwardly from a base 15 which is fastened to the floor of the vehicle. Mounted on the column for rotation about the axis thereof is a sleeve 16 which extends downwardly around the column 14 as indicated in Fig. 2.

The ladder is connected to the sleeve by a system of links which control its tilting movements. This system comprises two duplicate sets of links which are positioned at opposite sides of the sleeve 16. As shown in Fig. 2, each set of links comprises a strut 20, one end of which is pivotally connected as at 21 to a bracket 23 carried by the sleeve 16, and the other end of which is pivotally connected to the adjacent side rail of the base section 11 of the ladder, as at 24. A link 25 is also pivotally connected to the ladder at 24 and to a second link 26, as at 27. The link 26 in turn is pivoted to the sleeve 16 at a point 28 which is spaced from the pivot 21. The position of the struts 20 is determined by threaded shafts 30 which are carried by a housing 31 pivotally connected to the sleeve 16. The shafts 30 are simultaneously actuated by either wheel of a pair of hand wheels 32 secured to a cross-shaft 33. The shaft 33 is geared to the shafts 30 which coact with respective nuts pivotally mounted in enclosures 31 which are secured to the struts 20.

The ladder is transported from place to place in a horizontal position as shown by the dotted lines A in Fig. 1. When it is placed in use the operator draws the end 17 of the ladder downwardly and latches it to the pivotal connection 27 between the links 25 and 26. A suitable latch mechanism for this purpose is described in detail in the prior patent heretofore mentioned, but for the purpose of this application, it is sufficient to

state that the latch may be manually actuated, as for instance by a control member 18 (Fig. 5). After the ladder has been latched in its tilted position, indicated at B in Fig. 1, it may be adjusted by manipulation of the hand wheel 32 to the desired angle of tilt, as for instance, the positions C of Fig. 1.

The present invention is particularly concerned with an improved mechanism for counterbalancing the ladder to facilitate its movement to the tilted position and to maintain the strain on the tilting apparatus. This mechanism comprises a spring loaded plunger carried by and extending alongside the ladder and controlled by a system of parallel links which are connected to the sleeve 16.

As shown in the drawings, a link 35 is pivoted at one end, as at 36, to the bracket 23 and at its other end, as at 37, to a bracket 38, which in turn is pivoted to the ladder at the pivot 24 heretofore described. The arrangement is such that the pivots 36 and 21 are spaced horizontally from each other, and the pivots 37 and 24 are similarly spaced the same distance from each other. The links 35 are the same length as the struts 20 and thus form a system of parallel links, such that regardless of the angular movement of the struts 20, due to the operation of the ladder tilting mechanism, the pivots 37 and 24 remain horizontal, that is, parallel to the pivots 21 and 36.

The counterbalancing mechanism includes a spring loaded plunger 40 which is pivoted at 41 to an upstanding arm 42 of the bracket 38. This plunger extends alongside the ladder into a cylinder 43, the far end of which is pivoted at 44 to the ladder section 11. A pre-loaded spring 45 is interposed between an enlarged end 46 of the plunger and the end 47 of the cylinder.

By utilizing parallel links 20 and 35 to connect the bracket 38 to the collar 23, the part 38 is maintained in a vertical position during all increments of movement of the ladder about the pivot 24. As a result, the lifting force of the springs can be applied to the ladder in a degree more nearly approximating the shifting of the center of gravity of the ladder structure so as to cause a substantially balanced condition regardless of the position of the ladder with respect to the supporting structure. Normally, where the ladder is horizontal, the moment arm about the pivot 24 does not change as rapidly when the ladder is near a horizontal position as it does when the ladder approaches the vertical position. By maintaining the part 38 substantially vertical, however, during the swinging movement of the ladder, the springs are able to exert a counterbalancing force of substantially uniform degree regardless of the position of the ladder with respect to the supporting frame. As a result the operator can move the ladder, by applying substantially the same force thereto, in all positions of the ladder.

We claim:

1. In combination, a vehicle, a ladder, means for mounting the ladder for tilting movement on the vehicle, said means comprising a column rigidly attached to the vehicle, a sleeve supported by the column, and counterbalancing means connecting the sleeve and ladder, said last-mentioned means including a preloaded plunger pivotally connected to the ladder, and means for connecting the other end of the plunger to said sleeve, said last-named means including a system of parallel links one end of each link being pivotally connected to the sleeve, the other end of one link being pivotally connected with the

ladder, and with a lever, a pivotal connection between the other link and the lever and a pivotal connection between the preloaded plunger and said lever.

5. In combination, a vehicle, a ladder, means for mounting the ladder for swinging and tilting movement on the vehicle, said means comprising a column rigidly attached to the vehicle, a sleeve swivelled on the column, a pivotal connection between the sleeve and the ladder, and counterbalancing means connecting the sleeve and ladder, said last-named means including a preloaded plunger having one end pivotally connected to the ladder and extending alongside a rail of the ladder, a lever pivotally interconnecting the other end of said plunger with the ladder, and means to control the position of said lever including a pair of parallel links interconnected between the lever and the sleeve, each of said links being pivoted at one end to spaced points on said lever and at the other end to spaced points on said sleeve.

3. In combination, a vehicle, a ladder, means for mounting the ladder for tilting movement on the vehicle, said means comprising a column rigidly attached to the vehicle, a sleeve supported by the column, and counterbalancing means connecting the sleeve and ladder, said last-mentioned means including a preloaded plunger unit pivotally connected to the ladder, and a link pivotally interconnected between the other end of the plunger unit and said ladder, and a system of parallel links connecting said link to said sleeve.

4. In combination, a vehicle, a ladder, means for mounting the ladder for tilting movement on the vehicle, said means comprising a column rigidly attached to the vehicle, a member rotatably supported on the column, and counterbalancing means connecting the member and ladder, said last-mentioned means including a pair of parallel links, each link being pivoted at one end to the member at spaced points, one of said links having its other end pivoted to the ladder, a third link pivotally interconnecting said first-named links remote from the column to form a system of parallel links, and a preloaded spring connection between said third link and said ladder.

5. In combination, a vehicle, a ladder, means for mounting the ladder for swinging and tilting movement on the vehicle, said means comprising a column rigidly attached to the vehicle, a sleeve mounted on said column for swinging movement about a substantially vertically extending axis, a pivotal connection between the sleeve and ladder including a link pivoted at one end to said sleeve and at the other end to said ladder whereby said ladder may be tilted about a horizontal axis, a second link pivoted at one end to said sleeve, and connecting means pivoted to the pivotal connection between the first-named link and the ladder, and pivoted to the second-named link to maintain said links parallel, and a preloaded compression spring disposed between said connecting means and a point on said ladder remote from its pivotal connection with said first named link.

6. In combination, a vehicle, a ladder, means for mounting the ladder for swinging and tilting movement on the vehicle, said means comprising a column rigidly attached to the vehicle, a sleeve mounted on said column for swinging movement about a substantially vertically extending axis, a pivotal connection between the sleeve and ladder including a link pivoted at one end to said sleeve and at the other end to said ladder, whereby said ladder may be tilted about

a horizontal axis, a second link pivoted at one end to said sleeve and connecting means pivoted at the pivotal connection between the first-named link and the ladder and to the second-named link to maintain said links parallel, a plunger member, a cylinder member cooperating therewith, a compression spring coacting with the plunger and cylinder and tending to move them together, a pivotal connection between one of said members and said connecting member, and a pivotal connection between the other of said members and said ladder at a point remote from its pivotal connection with said first-named link.

7. In combination, a vehicle, a ladder, means for mounting the ladder for swinging and tilting movement on the vehicle, said means comprising a column rigidly attached to the vehicle, and a sleeve swiveled on the column, and a strut pivotally connected to the sleeve and to the ladder, and an additional connection between the sleeve and ladder comprising a pair of links pivotally joined together, said means also including a screw and nut couple connecting said strut and the sleeve for moving the ladder with reference to the sleeve, means for actuating one member of the couple, a link pivoted at one end to said sleeve, means interconnecting the pivotal connection between the strut and said ladder with the last-named link to maintain said link parallel with said strut at all times, and a pre-loaded compression spring positioned between said connecting means and a point on said ladder remote from its pivotal connection with said first-named link to counterbalance said ladder.

8. In combination, a support, a ladder mounted on said support for swinging movement in a substantially vertical plane, a counterbalance for said ladder including a telescoping preloaded spring cylinder, a lever, a pivotal connection between one end of said cylinder and the ladder, a pivotal connection between the other end of said cylinder and the lever, a pivotal connection between the other end of said lever and the ladder, means to control the swing of said lever about its pivotal connection with said ladder and thereby control the counterbalancing force of said spring cylinder, and wherein said last named means includes a pair of parallel links, said links being pivotally connected at one end to respective spaced points on said lever, one of said last named connections being coincident with the pivotal connection between the lever and the ladder, and pivotal spaced connections between the other ends of said links and said support.
